UNITED STATES PATENT OFFICE

WILLIAM JOSEPH BYRNE, OF INDIANAPOLIS, INDIANA

HAT PRESSING MACHINE

Application filed November 15, 1930. Serial No. 495,819.

This invention relates to the art of hat pressing machines of the type employing a sand bag.

A primary object of the invention is to provide a structure whereby the sand bag may be readily raised and lowered without the exercise of any great amount of energy upon the part of the operator.

Other objects reside in the particular novel combination of the various elements entering into the structure permitting not only the ease of operation of the machine but also allowing of a low cost of production and use of the machine.

These and other objects will become apparent in the following description of the invention as illustrated in one particular form in the accompanying drawings, in which

Fig. 1 is a fragmentary side elevation of a machine employed in my invention;

Fig. 2, is a rear elevation of the machine;

Fig. 3, a horizontal section on the line 3—3 in Fig. 1;

Fig. 4, a vertical section on the line 4—4 in Fig. 1; and

Fig. 5, a detail in front elevation of the foot pedal latch structure.

Referring to the drawings, in which like characters of reference indicate like parts in the several views, I provide a hollow table 10 having steam connections 11 and 12 whereby steam may be circulated through the interior of the table to heat the top thereof. I mount this table 10 upon a tripod having the three legs 13, 14 and 15. Between the legs 14 and 15 I fix a pair of angle bars 16 and 17 spaced apart in vertical positions. Between the upper ends of these bars 16 and 17 I pivotally mount a rocker member by means of the central bar 18 on the outer ends of which are arcuate channels 19 and 20. The upper ends of these channels are joined by a channel bar 21 whereby a continuous groove is formed from around over the members 19, 21 and 20.

To the forward end of the channel bar 21 I fix the end of a chain or flexible cable 22 and carry the cable around the channel bar 19 and down to the sand bag 23 which is formed in the usual manner well known to those versed

in the art. This sand bag generally weighs in the neighborhood of sixty pounds. Toward the rear end of the channel bar 21 I fix the cable 24 and carry it rearwardly and around downwardly from the channel member 20 to a weight 25 fixed on its lower end. The sand bag 23 and weight 25 are balanced one between the other over the rocker member above described as carried by the bars 16 and 17.

In order to permit the sand bag 23 to exert its full weight toward the table 10, it is necessary to relieve the pull of the weight 25 therefrom and for this purpose I provide a mechanism which I shall now describe.

Between the lower ends of the upright bars 16 and 17 I pivotally mount a foot lever 26 to have its forward end extend through a loop 27 fixed on the side of the leg 13. A weight 28 fixed on the opposite end of the lever 26 tends to rock the forward end against the upper side of the loop 27. An ear 29 is provided to project outwardly from the leg 13 with an inclined upper surface so that the lever 26 may be pushed downwardly and moved laterally to engage under the ear. Behind the bars 16 and 17 I pivotally attach a guide bar 30 by its lower end to the lever 26. The upper end of the bar 30 is slotted to engage over a pin 31 projecting laterally from the central arm 18. On the bar 30 below the slot therein, I pivotally mount the lever 32, the lower end of which has an arm 33 extending substantially rearwardly at right angles thereto, the outer end of which is pivotally attached to the connecting link 34. The lower end of this link 34 is pivotally carried on the bolt 35 which also pivots the bar 30 to the lever 26.

The bar 30, Fig. 4, is loosely fitted about the bolt 35 so that the bolt 35 may travel in relation thereto as the link 34 may be raised or lowered upon rocking of the lever 26. The lever 32 is provided with the two spaced apart engaging shoulders 36 and 37 normally behind the pin or bolt 31. A strap 38 is fixed by its ends by the bolts 39 and 40 to the cross arm 18 to retain the lever 32 and the bar 30 in sliding engagement thereto as the rocker member may be shifted.

upon change in the position of the sand bag 23.

Normally, it is desired that the sand bag 23 be resting upon the table 10 so as to be 5 absorbing heat therefrom. To place the sand bag in that position, the bag is grasped by the handles 41 and 42 and pulled downwardly to contact the table. This operation is accomplished with slight physical exertion on 10 account of the counterweight 25 tending to balance the sand bag. However unless the pull of the weight 25 is released the sand bag will not settle down firmly against the top of the table 10. Accordingly, the foot lever 26 15 is pushed down by its front end and engaged over the ear 29, during which travel, the link 34 has pushed up on the arm 33 to rock the lever 32 forwardly to engage the pin 31. With the sand bag 23 in contact with the 20 table 10, the cross arm 18 has been rocked to carry the pin 31 upwardly to push back the shoulder 37 and as the lever 26 is pushed downwardly by its forward end, this shoulder 37 swings in under the pin 31 and pushes 25 upwardly on it to rock the arm 18 and its attached members further around to elevate the weight 25 and release the pull on the cable 22, whereby the sand bag 23 flattens out and rests upon the table under its full 30 weight and without any upward pull.

When the machine is to be used, the lever 26 is released from under the ear to lower the weight 25 and rock the channel members 20, 21 and 19 around to permit the weight 35 25 to cause a pull to be exerted on the cable 22 and thus tend to lift the sand bag 23. The bag 23 may then be lifted easily with aid of the weight 25 and a block 43 may be placed upon the table with a hat 44 inverted 40 thereover. The sand bag 23 still retaining the heat absorbed from the table 10 is pulled down to rest on and press the brim of the hat against the block 43.

When the sand bag 23 contacts the hat 44, 45 the pin 31 has then been rocked upwardly to be pulled above the line of the shoulder 36. The lever 26 is then pulled down by its front end to cause the shoulder 36 to be swung under the pin 31 and to push upwardly 50 thereon to lift the weight 25 and relieve the pull on the cable 22 so as to allow the sand bag 23 to settle down by its own weight over the brim of the hat 44. When the pressing operation is completed the lever 26 is released 55 from under the ear 29 and the weight 25 is allowed to be lowered thereby so as to return the pull on the cable 22 and permit the easy raising of the sand bag 23.

The lever 32 normally tends to swing rearwardly by its upper end by reason of the pull of gravity so as to normally carry the shoulders 36 and 37 rearwardly from under the pin 31.

While I have here shown and described 60 my invention in the one form as now best

known to me, it is entirely obvious that structural changes may be made from that form without departing from the spirit of the invention, and I, therefore, do not desire to be limited to that precise form, nor any more than may be required by the following claims. 70

I claim:

1. In a hat pressing machine, a table, an upright member behind the table, a rocker pivotally supported above the table, a sand bag, a flexible connection between the bag and the rocker, a weight connected to the rocker on the opposite side of its pivoted point from said bag connection, means for lifting said weight, said means comprising a foot pedal, a guide bar pivotally connected to the pedal and slidably guided across the rocker, a lever pivoted to the bar, a link pivoted to an arm of the lever and to the pedal, a pin on the rocker, and shoulders on the lever adapted to be swung under and up against said pin. 80

2. In a hand operated hat pressing machine, a table, a rocker pivotally supported above the table, a pressing element hung from the rocker, a weight hung from the rocker to counter balance the pressing element, said element being free to be raised and lowered by hand and adapted to remain at any elevation where left under the influence of said weight, 90 a pin projecting from the rocker, a bar having a slot through which the pin passes, a lever pivoted to the bar having a shoulder thereon, and means for rocking and raising the lever and raising the bar to shift said shoulder under the said pin and rock said rocker, whereby said element may selectively settle on said table with the pull of said weight thereon removed. 95

3. In a hand operated hat presing machine, a table, a rocker pivotally supported above the table, a pressing element hung from the rocker, a weight hung from the rocker to counter balance the pressing element, said element being free to be raised and lowered by 100 hand and adapted to remain at any elevation where left under the influence of said weight, a pin projecting from the rocker, a lever having a shoulder thereon, and means for rocking and raising the lever to shift said shoulder under the said pin and rock said rocker, whereby said element may selectively settle on said table with the pull of said weight thereon removed, said means comprising a 110 foot pedal and a bar having its lower end loosely mounted on said pedal and its upper end guided to permit vertical reciprocation, said first lever being rockably carried by said bar, and a link pivotally interconnecting said lever and said foot pedal. 115

4. In a hand operated hat pressing machine, a table, a rocker pivotally supported above the table, a pressing element hung from the rocker, a weight hung from the rocker to counter balance the pressing element, said 120

125

130

element being free to be raised and lowered by hand and adapted to remain at any elevation where left under the influence of said weight, a pin projecting from the rocker, a lever 5 having a shoulder thereon, and means for rocking and raising the lever to shift said shoulder under the said pin and rock said rocker, whereby said element may selectively settle on said table with the pull of said 10 weight thereon removed, said means comprising a foot pedal and a bar having its lower end loosely mounted on said pedal and its upper end guided to permit vertical reciprocation and having a slot through which the pin 15 passes, said first lever being rockably carried by said bar and having a lateral extension, and a link pivotally interconnecting the lateral extension of said lever and said foot pedal, said link being connected to said lever 20 to cause forward and rearward travel of the said shoulder upon lowering and raising of said pedal.

In testimony whereof I affix my signature.

WILLIAM JOSEPH BYRNE.
